Primary Examiner — T Chase Nelson(74) *Attorney, Agent, or Firm* — Marshall A. Lerner; Steven J. Kim; Kleinberg & Lerner, LLP(57) **CLAIM**

The ornamental design for a shoe midsole periphery, as shown and described.

DESCRIPTION

FIG. 1 is a perspective view of a shoe midsole periphery in accordance with my new design; and,

FIG. 2 is a left side elevation view thereof.

The broken lines shown in the drawings represent portions of the shoe midsole periphery that form no part of the claimed design.
